Primary Examiner — John Windmuller*Assistant Examiner* — John R Yeh**CLAIM**

(57) The ornamental design for a hand held cleaning sponge handle, as shown and described.

DESCRIPTION

FIG. 1 is a front perspective view of my new design for a hand held cleaning sponge handle;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is another perspective view of.

The broken lines in the figures illustrate a portion of the handle and environment that form no part of the claimed design.
